United States Patent Office.

ELIAS INGRAHAM, OF BRISTOL, CONNECTICUT.

Design No. 4,948, dated May 30, 1871.

DESIGN FOR CLOCK-CASE SASH.

The Schedule referred to in these Letters Patent and making part of the same.

I, ELIAS INGRAHAM, of Bristol, in the county of Hartford and State of Connecticut, have invented or produced a new and original Design for a Clock-Case Sash, of which the following is a specification.

My design consists of radial sections of light and dark woods, alternating each other throughout the sash and rosettes of a clock-case, sash, or door.

In the accompanying drawing—

Figure 1 is a front elevation of a clock-sash or door embodying my invention or design.

Figure 2 is a like view of another sash embodying the generic features of my design.

Figure 3 is a front view of a single sash and rosettes embodying my invention.

The two sashes A A, rosettes B B, and their connection C, are old when they consist of one color only.

In my design these parts consist of radial sections—that is, sections meeting each other on radial lines—of light and dark woods or material a b.

These radial sections a b are alternately arranged throughout each sash A and rosette B, as shown, thus forming a lively and attractive design.

I do not wish to confine myself exclusively to the two sashes and rosettes for a single sash, as I contemplate using the upper sash and rosettes separated from the lower sash, as shown in fig. 3.

The cases to which the sash is applied may, of course, vary so as to extend each way of the sash, or conform to the contour of the sash, when said sash becomes the whole front of the clock-case.

I claim as my invention—

1. The design for the whole clock-case sash, as shown in fig. 1.

2. The design for the sash A, consisting of alternate radial sections of light and dark woods a b, substantially as shown and described.

3. The design for the rosette B, consisting of alternate radial sections of light and dark woods a b, substantially as shown and described.

ELIAS INGRAHAM.
